UNITED STATES PATENT OFFICE.

FRED H. HEUMANN, OF SEWARD, NEBRASKA.

SHOCKER.

1,175,758.

Specification of Letters Patent. Patented Mar. 14, 1916.

Application filed June 7, 1915. Serial No. 32,640.

To all whom it may concern:

Be it known that I, FRED H. HEUMANN, a citizen of the United States, residing at Seward, in the county of Seward and State 5 of Nebraska, have invented new and useful Improvements in Shockers, of which the following is a specification.

My present invention pertains to shockers for use on harvester binders; and it consists 10 in the shocker, hereinafter described and claimed, constructed and arranged to perform the following functions, viz: to receive bundles of grain from a binder, form the bundles into a shock, move the shock to 15 upright position, with the heads of the grain uppermost, by swinging movement of the shock former, compress the head of the shock while it is in the former and until the shock is stood on the ground, instantly release the shock to enable it to stand in the stubble of the field, and finally return the former to its initial position ready for the 20 reception of the bundles to constitute another shock.

25 The operation of the shocker is manually controlled, and is intended to take place while the operation of the bundle elevator of the binder is suspended; the bundle elevator being placed in operation when the 30 shocker operating means is placed out of operation and vice versa.

With the foregoing in mind, the invention in all of its details will be fully understood from the following description and claims 35 when the same are read in connection with the drawings, accompanying and forming part of this specification, in which:

Figure 1 is a side elevation illustrating 40 the shocker constituting the best practical embodiment of my invention that I have as yet devised, as the same appears at the side of a harvester binder. Fig. 2 is a plan view of the same. Fig. 3 is a front elevation, with parts in section. Fig. 4 is a detail 45 rear elevation showing the former and the clamps therein, together with certain appurtenances of the clamps. Fig. 5 is an enlarged detail of the door-latching means complementary to the former. Fig. 6 is a 50 detail section showing one of the slides 15 and its appurtenances as properly arranged relatively to the former.

Similar numerals of reference designate 55 corresponding parts in all of the views of the drawings.

My novel shocker is attached to and car-

ried by the harvester binder, and, among other elements, it comprises a shock former 1, having an opening 1^a at its upper side for the reception of bundles from the elevator of the binder. The scheme of my invention contemplates the putting of a shaft 2 in gear by the operator as soon as the former 1 is full; and it also contemplates that the said shaft 2 be automatically thrown out 60 of gear when it shall have turned through one complete revolution, the means for accomplishing this being hereinafter set forth in detail.

The former 1 is fixed at the upper portion 70 of its front end to a transversely-disposed shaft 3, and this shaft 3 is journaled at its ends in the sides of a reciprocator or rearwardly and forwardly movable carrier 4. The said sides of the carrier 4 are equipped 75 with traveling wheels 5 and these are supported and guided by and are adapted to move on longitudinally-disposed channel beams 6, fixed to the binder frame.

A crank 7 is fixed to one end of the shaft 80 2, and is connected through a rod 8 with the carrier 4, and from this it follows that rotation of the said shaft 2 through a part (say one half) of a revolution will be attended by rearward movement of the carrier 4 on 85 the beams 6, while the rotation of the shaft 2 through the remainder of the revolution will be attended by reverse or forward movement of said carrier 4. It will also be noticed that the shaft 3 on carrier 4 is provided with 90 a crank 8^a, and that said crank is connected through a pivoted rod 9 with a fixed and suitably braced upright 10 on one of the beams 6.

95 Incidental to the described rearward movement of the carrier 4,—i. e., movement of the carrier 4 in the direction indicated by arrow in Fig. 1, and by the rocking of the shaft 3 through the medium of the crank 8^a, rod 9 and frame 10, just described, the former 1 is caused to swing upwardly on the center 100 of the shaft 3 from its initial horizontal position to an upright position, in which latter position the discharge end of the former 1 will be in approximately the same horizontal plane as the shaft 3.

105 Disposed at the inner sides of the side portions of the shock-former 1 are clamps 11 for compressing the head of the shock incidental to the downward movement of the shock to the ground. The said clamps 11 are caused to compress the head of the

shock by draft on cables 12 due to the upward and forward swinging movement of the shock-former 1 and the rearward movement of the carrier 4. The cables 12 are connected through retractile springs 13 with the fixed uprights 10 on the beams 6, and are passed over the sheaves 14 on slides 15 and attached at 16 to laterally disposed rods 19 which are connected to the clamps 11 and 10 extend loosely through the slides 15.

When the shock-former 1 reaches its upright position the clamps 11 are pulled together, and the lever-latches 17 on the slides 15 move into notches 18 in the rods 19. This has the effect of holding the clamps 11 in position to compress the head of the shock during the gravitation of the shock to the ground. The slides 15 serve to hold the clamps 11 in position, and are arranged and movable in grooves 20 in the side portions of the former 1.

Expansion springs 22 on the rods 19 are interposed between the slides 15 and abutments 23 on the rods so that the springs are compressed or put under tension by inward movement of the rods and hence operate when the rods are relieved of pull, to quickly move the rods and the clamps 11 outwardly.

25 25 is a lever for retaining the slides 15 in their rearmost positions and at the same time holding the door 26 at the forward end of the former 1 in its closed position. The said lever 25 is provided with a U-shaped portion, the arms 27 of which are fulcrumed on the former 1, at the points 28. The said lever 25 is connected through a rod 30 with one arm of a latch lever 31. This latch lever is fulcrumed at 32 on the underside of the former 1, and its other and forward arm 35 is provided with a beveled head 33 to engage a lug 34 on the door 26. The door 26 is connected in hinged manner to the shaft 3, and hence when the former 1 is in upright position and the lever 31 is disengaged from 40 the lug 34, the door 26 will be free to gravitate until it is in pendent position against a transversely-disposed stop 40 on the carrier 4.

50 As the former 1 moves to its upright position, the lever 25 engages a stop 41 supported by uprights 42 on the beams 6. This engagement rocks the lever 25 and thereby releases the slides 15 and the door 26. Thereupon the shock, the clamps 11 and the slides 15 move downwardly out of the former. The slides 15 also move in guideways 44 which form continuations of the slots 20 until the latch levers 17 strike trips 45 on the said guideways 44 when the springs 55 22 will operate to immediately move the clamps 11 apart or away from each other, and the shock will be left on end on the ground and firmly embedded in the stubble. This is an important feature of my invention since it is essential to successful han-

dling of the shock that the head of the same be compressed while the shock is leaving the machine and until it strikes the ground. To yieldingly retain the lever 25 in proper position until it strikes the stop 41, I provide a retractile spring 50 interposed between the lever and the shock-former 1, as 70 illustrated.

The operation hereinbefore described takes place during the rotation of the shaft 75 2 through a part, preferably one half, of a revolution.

51, 51 are metallic flanges fixed to the carrier 4 and arranged to slide inside and underneath channel beams 6. Incidental to 80 the rotation of the shaft 2 through the remainder of the revolution, the carrier 4 is moved forwardly relative to the direction in which the machine is moved, whereupon the former 1 will be swung back to its initial 85 horizontal position, and the door 26 will be latched in closed position. While the former 1 is moving from the upright position to the initial horizontal position, cables 55 interposed between and connected to the 90 slides 15 and the uprights 42 operate to return the slides 15 and the clamps 11 to their original positions, and the lever 25 will automatically lock said slides in said positions. 95

To drive and control the operation of the shaft 2, the organized mechanism, which will now be described in detail, is provided.

At the opposite end of the shaft 2 with reference to the crank 7, is a beveled gear 100 60 with which is intermeshed a gear 61 on a shaft 62, journaled in uprights 63 on one of the channel-beams 6. Mounted to slide on and turn with the shaft 62 is a clutch member 64, and loosely mounted on said 105 shaft 62 is an opposed clutch member 65 to which is fixed a sprocket gear 66. Also fixed with respect to the clutch member 65 is a sprocket gear 67. Connecting a sprocket gear 68 on the pitman shaft 69 of the harvester binder with the sprocket gear 66 is a sprocket belt 70. The sprocket gear 67 is designed through a sprocket belt 71 to drive a sprocket gear 72, loose on the lower shaft 73 of the bundle elevator of the harvester 115 binder. Fixed to the said gear 72 is a clutch member 74; and opposed to said clutch-member 74 is a clutch member 75, mounted to turn with and slide on the shaft 73. The upper shaft 76 of the bundle elevator is 120 driven from the shaft 73 through the intermeshed gears 77 and 78.

80 and 81 are levers, loosely connected together at 82. The lever 80 is connected to the clutch member 64, and the lever 81 125 is connected to the clutch member 75. It will also be noticed that a cable 84 is connected to the lever 80. This cable 84 is connected to a foot lever (not shown) on the harvester binder; the said foot lever being 130

preferably disposed in the same position as the foot lever ordinarily employed to control the bundle carrier of the machine. It will be readily apparent from the foregoing 5 that a pull on the cable 84 will be attended by clutching of the sprocket gear 66 to the shaft 62 and the unclutching or disconnection of the sprocket gear 72 from the shaft 73. This synchronously stops the bundle 10 elevator and puts the shocker in operation. As will be observed by reference to the drawings, the lever 80 is provided at its lower end with an upwardly extending arm 90.

15 Immediately before the carrier 4 reaches the extremity of its before described forward traverse, the said carrier strikes the arm 90 of the lever 80 and thereby disconnects the gear 66 from the shaft 62 to render 20 the shocker idle, and at the same time connects the gear 72 with the shaft 73 to re-establish the operation of the bundle elevator.

The bundle elevator *per se* constitutes in 25 itself no part of my invention and it may therefore be of the conventional or of any other construction compatible with the purpose of my invention.

While the rods 19 on the clamps 11 are 30 shown as circular in cross-section, it is obvious that the said rods may be of any angular form in cross-section when deemed desirable with a view to utilizing said rods 19 to prevent swinging of the clamps 11 in 35 the former 1.

Having described my invention, what I claim and desire to secure by Letters-Patent, is:

1. In a shocker, the combination of a 40 swinging shock former, a reciprocatory carrier on which the shock former is mounted, shock compressing means in the former, means for reciprocating the carrier, means actuatable by reciprocation of the carrier for 45 swinging the former, and means actuatable by the reciprocation of the carrier and the swinging of the former for operating the shock-compressing means.

2. In a shocker, the combination of a 50 swinging shock former having an end door, a reciprocatory carrier on which said former is mounted, means for reciprocating the carrier, means actuatable by reciprocation of the carrier for swinging the former, means for 55 latching the end door of the former, and means for releasing said end door on swinging of the former.

3. In a shocker, the combination of a 60 swinging shock former having an end door, shock-compressing means in the former, means for latching the end door and the shock-compressing means, means for reciprocating the carrier, means actuatable by reciprocation of the carrier for swinging the 65 former, means actuatable by reciprocation of

the carrier and swinging of the former for operating the compressing means, and means for releasing the end door and the compressing means on swinging of the former.

70

4. In a shocker, the combination of a 75 swinging shock former, a reciprocatory carrier on which the former is mounted, means actuatable by reciprocation of the carrier for swinging the former, the bundle elevator of a harvester and binder, means for reciprocating the carrier and actuating the bundle elevator, normally controlled means for synchronously putting the bundle elevator out of operation and the carrier in operation, 80 and means operated by the return movement of the carrier for putting the carrier out of operation and the bundle elevator in operation.

5. In a shocker, the combination of a 85 swinging shock former, a reciprocatory carrier on which the former is mounted, means actuatable by reciprocation of the carrier for swinging the former, the bundle elevator of a harvester and binder, means for reciprocating the carrier and actuating the bundle elevator, normally controlled means for synchronously putting the bundle elevator out of operation and the carrier in operation, 90 shock-compressing means in the shock former, means actuatable by reciprocation of the carrier and swinging of the former for operating said compressing means, and means operated by the return movement of the carrier for putting the carrier out of 95 operation and the bundle elevator in operation.

6. In a shocker, the combination of a 100 shock-former, means for manipulating the same, shock-compressing clamps in the 105 former, means for moving said clamps toward each other during swinging movement of the former, means for holding the clamps against movement longitudinally of the former during swinging of the former, 110 means for suddenly releasing the clamps when the former is in upright position, and means for restoring the clamps to and securing the same in their initial positions when the former is restored to its initial 115 position.

7. In a shocker, a shock former constructed and arranged to be swung upwardly and forwardly on a center located adjacent to its upper and forward corner, means actuatable by movement of the former for compressing a shock during movement of the former, means for releasing and permitting downward endwise movement of the shock while under compression, and means for 120 suddenly releasing the shock to stand the same on end.

8. In a shocker, a shock former constructed and arranged to be swung upwardly and forwardly on a center located adjacent to its 125

130

upper and forward corner, a rectilinearly movable carrier in which the former is mounted, means carried by and movable with the former and actuatable by movement of the former and carrier for compressing a shock during movement of the former and carrier, means for releasing and permitting downward endwise movement of the shock while under compression, and means for suddenly releasing the shock to stand the same on end.

9. In a shocker, the combination of a shock former movable from a horizontal position to an upright position, means for operating said former, means for compressing the head of a shock as the shock moves downwardly relatively to the former; said means being movable inwardly on movement of the former to its upright position and being also movable downwardly with respect to the former, means for moving the compressing means inwardly, and means

for suddenly releasing the compressing means as the shock is deposited on the ground.

10. In a shocker, the combination of a shock-former movable from a horizontal position to an upright position, a reciprocatory carrier on which the shock former is mounted, shock compressing means also mounted on the carrier, means actuatable by reciprocation of the carrier for moving the former, and means actuatable by the reciprocation of the carrier and the movement of the former for operating the shock-compressing means.

In testimony whereof I have hereunto set my hand in presence of two subscribing witnesses.

FRED H. HEUMANN.
